THOMAS N. DIXON AND CHARLES FRIESE, OF PHILADELPHIA, PENNSYLVANIA, ASSIGNORS TO THOMAS S. DIXON & SONS, OF SAME PLACE.

Design No. 4,974, dated June 6, 1871.

DESIGN FOR GAS FIRE-LOGS.

The Schedule referred to in these Letters Patent and making part of the same.

To all whom it may concern:

Be it known that we, THOMAS N. DIXON and CHARLES FRIESE, of Philadelphia, in the county of Philadelphia and State of Pennsylvania, have invented a new and improved Design for Gas Fire-Logs; and we do hereby declare that the following is a full, clear, and exact description thereof, which will enable others skilled in the art to make and use the same, reference being had to the accompanying drawings forming part of this specification.

Our improved design for gas fire-logs, represented in the accompanying photographs, embraces the following distinct and separate features, and the whole in combination, as hereinafter described, the said logs being made of clay or other suitable substance:

First, the parts representing sticks or logs having representations of bark skinned, split, or knocked off in different places, as represented at A A.

Second, the sticks or logs having clumps representing bunches of moss, as shown at B B B B.

Third, the sticks having the bark surrounding the knots shrunk or dried away from around the edge of the knots, as shown at C C.

Fourth, the said imitation sticks having real cracks in the ends and other places, in imitation of the natural cracks of wood, as shown at D D D D.

Fifth, the said sticks having the appearance of the ends of sticks of wood cut off obliquely and jaggedly, as shown at E.

Sixth, the sticks having the representation of being cut off obliquely, with centers formed and colored to look as if decayed, as shown at F.

Seventh, the ends represented as broken off, as shown at G.

Eighth, the ends represented as being cut off obliquely, as shown at H.

Ninth, the sticks having the representations of miscuts of an axe, as shown at J J.

Tenth, the sticks represented in variegated colors, and some in lighter colors than others, as shown at K.

Eleventh, the sticks having the representation of splinters of wood, as shown at L L L L, the said representation being imparted by asbestos fiber fixed to the sticks at an angle, which fibers catch the flame and, becoming incandescent, have the appearance of burning splinters.

We claim as our invention—

1. The design for gas-logs represented at A, substantially as shown and set forth.
2. The design for gas-logs as represented at B, substantially as shown and set forth.
3. The design for gas-logs as represented at C, substantially as shown and set forth.
4. The design for gas-logs as represented at D, substantially as shown and set forth.
5. The design for gas-logs as represented at E, substantially as shown and set forth.
6. The design for gas-logs as represented at F, substantially as set forth.
7. The design for gas-logs as represented at G, substantially as set forth.
8. The design for gas-logs as represented at H, substantially as set forth.
9. The design for gas-logs as represented at J, substantially as set forth.
10. The design for gas-logs as represented at K, substantially as set forth.
11. The design for gas-logs as represented at L, substantially as set forth.
12. The design for gas-logs comprising the specific features in combination as enumerated in the foregoing clauses of claims, substantially as represented in the accompanying photographs.

THOMAS N. DIXON.
CHARLES FRIESE.
